UNITED STATES PATENT OFFICE

VITO GALIZIA, OF PLAINFIELD, NEW JERSEY

AUTOMATIC RAILROAD-CROSSING GATE

Application filed August 18, 1927. Serial No. 213,908.

This invention relates to automatic railroad crossing gates, and has for its principal object to provide vertically sliding gates and means including track switches for automatically raising the gates to closed position upon the approach of a train to the crossing and for lowering the gates to open position after the passage of said train.

A further object is to provide an apparatus 10 of the above character which is of extremely simple and durable construction as well as efficient and reliable in operation.

Other objects will become apparent as the 15 nature of the invention is better understood, and the same consists in the novel form, combination and arrangement of parts herein-after more fully described, shown in the accompanying drawings and claimed.

In the drawings, wherein like reference 20 characters indicate corresponding parts throughout the several views,

Figure 1 is a fragmentary top plan view illustrating the location of the gates and track switches, and other details;

Figure 2 is a fragmentary vertical longitudinal section taken upon line 2-2 of Figure 1;

Figure 3 is a vertical transverse section taken upon line 3-3 of Figure 1;

Figure 4 is an enlarged fragmentary vertical section through one of the track switches upon line 4-4 of Figure 1;

Figure 5 is a wiring diagram of the gate operating and controlling means for each 35 pair of gates; and

Figure 6 is a wiring diagram of the gate illuminating means and controlling switches therefor.

Referring more in detail to the drawings, 40 5 and 6 represent the tracks of a railroad and upon which traffic is adapted to travel as respectively indicated by the arrows *a* and *b*. Arranged across the roadway at opposite sides of the tracks are gates 7 and 8 operatively connected to an actuating motor 9 of the reversing type controlled by track switches 10 and 11 and arranged adjacent one of the rails of the track 5 at opposite sides of and some distance from the crossing.

50 A further pair of gates 12 and 13 are ar-

ranged across the roadway at opposite sides of the track, and these latter gates are operatively connected to a reversing motor 14 controlled by track switches 15 and 16 arranged adjacent one of the rails of the track 6 and at 55 opposite sides of and some distance from the crossing.

As shown clearly in Figures 1 to 3 inclusive, the gates are of the vertically sliding type and are vertically movable downwardly into or upwardly out of hollow open top casings 17 which are embedded in the ground and which connect pairs of hollow uprights or pillars 18. The pillars 18 are provided with vertical elongated slots 19 in the inner sides thereof into which the ends of the top and bottom rails of the gates slidably project, whereby the gates are effectively guided in their vertical sliding movement. The pillars 18 project above the ground and the surface of the casing 17, and it will be seen that the gates are adapted to be opened by lowering the same below the surface of the ground and are adapted to be closed by raising the same to a position where it may project upwardly out of the casings 17 and above the ground.

A longitudinal shaft 20 is journaled horizontally below each gate and has a pair of winding drums 21 fixed thereon, one within the lower end of each of the adjacent pair of pillars 18. Cables 22 are attached to the ends of the upper rail of each gate and these cables pass upwardly over guide pulleys 23 suitably journaled in the upper ends of the adjacent pillars 18, and then downwardly into the latter where they are attached to the winding drums 21 of the operating shaft 20 for said gates. The operating shaft of gate 7 is connected to the armature shaft of motor 9 and is also operatively connected to the operating shaft 20 of gate 8 by means of a sprocket gearing generally indicated at 24. In a like manner, the shaft 20 of gate 12 is connected to the armature shaft of motor 14 and is also operatively connected to the shaft 20 of gate 13 by means of a sprocket gearing 25. It will thus be seen that when the motor 9 is placed into operation with the armature shaft thereof turning in one direction, the 100

cables 22 of gates 7 and 8 will be wound upon the associated winding drums 21 for raising said gates 7 and 8 to closed position, a like operation taking place with respect to gates 12 and 13 when the motor 14 is placed into operation with its armature shaft turning in one direction. Obviously, reversing of the motors 9 and 14 will effect unwinding of the cables for permitting lowering of the gates respectively operated thereby, to open position. As shown, the sprocket gearings 24 and 25 extend transversely of and beneath the tracks, while the motors 9 and 14 are located in suitable pits beside the tracks.

It is intended that the motor 9, and consequently gates 7 and 8, be controlled by traffic moving upon the tracks 5 through actuation of the switches 10 and 11 by the car wheels, and that operation of motor 14 and consequently gates 12 and 13 be controlled by traffic moving on track 6 through actuation of track switches 15 and 16. As the controlling means for each motor and its associated pair of gates is the same, specific description of one will suffice for both. As shown in Figure 4, the track switches are normally opened, and each includes a casing 26 within which are mounted a pair of spaced contacts 27 and 28 having overlapping ends and normally tensioned to separate. Slidably mounted through the top of the casing 26 is a normally raised spring pressed plunger 29 adapted to be forced downwardly to cause engagement of contact 27 with contact 28, and overlying the plunger 29 is the higher end of a pivoted ramp 30 adapted to be depressed by the flange of the car wheels passing thereover for depressing plunger 29 and engaging contact 27 with contact 28. A suitable strong spring 31 is provided beneath ramp 30 for normally holding the same in raised position. As shown in Figure 5, the contact 27 of switch 10 is connected by a conductor 32 to one return terminal of motor 9, the cooperating feed terminal of which is connected by conductor 33 with the positive side of a suitable source of electricity 34. Mounted within one of the pillars 18 in the path of projections 35 and 36 on the adjacent end of gate 7, is a snap switch 37, one terminal of which is connected by conductor 38 to the negative side of the source 34, and the other terminal of which is connected by conductor 39 with contact 28 of switch 10. It will of course be understood that the operating lever of switch 37 is the part which is really in the path of the lugs 35 and 36, and the switch 37 is so arranged that when the operating lever thereof is swung downwardly connection between conductors 38 and 39 is made and when said lever is swung upwardly the connection is broken. Thus, when the gate 7 is lowered the switch 37 is engaged by lug 36 to close switch 37 and when

contacts 27 and 28 are engaged by operation of switch 10, due to approach of a train to the crossing on track 5 from the left of Figure 1, the motor 9 will be placed into operation for raising gates 7 and 8, and as soon as said gates are raised, the lug 35 will open switch 37 to throw the motor 9 out of operation. The other feed terminal of motor 9 is connected to the positive side of the source 34 by means of a conductor 40, and the other return terminal of said motor 9 is connected by conductor 41 with the contact 27 of switch 11 whose other contact 28 is connected by conductor 42 to one terminal of a switch 43 similar to switch 37. This switch 43 is mounted in the other pillar 18 at the opposite end of gate 7 with its lever in the path of lugs 44 and 45 carried by the adjacent end of gate 7, and the other terminal of said switch 43 is connected by conductor 47 with the return side of the source 34. The switch 43 is so arranged that when the gate 7 is raised, lug 45 will close the switch 43 and connect conductors 42 and 47 so that when the train passes the crossing and causes engagement of contacts 27 and 28 of switch 11, the motor 9 will be placed into operation for rotating in a reverse direction and unwinding the cables to lower gates 7 and 8. When the gate 7 lowers to open position, the lug 46 will engage the lever of switch 43 to open said switch and break the connection between conductors 42 and 47 whereby the motor 9 is stopped at the proper time when switch 37 is again closed by engagement of lug 36 with the lever of the latter. Obviously, switches similar to switches 37 and 43 are similarly associated with gate 12 and the motor 14 is similarly controlled by switches 15 and 16 as explained relative to the control of motor 9 by switches 10 and 11. Further, when only one track is encountered, such as the track 5, the gates 8 and 12 will be mounted adjacent the opposite side of said track from which gates 7 and 13 are disposed, and the switches 15 and 16 will be mounted adjacent the rail and track 5 other than that adjacent which the switches 10 and 11 are disposed, in either case, the ramps of switches 10 and 11 project in an opposite direction from that of the ramps of switches 15 and 16.

Mounted centrally of the roadway at opposite sides of the tracks are posts 48 having signal lamps 49 mounted upon the upper ends thereof controlled by normally open track switches 50 and 51 respectively mounted adjacent a rail of track 5 outwardly of switch 10 and adjacent a rail of track 6 outwardly of switch 15. As shown in Figure 6, the contacts 28^a of switches 50 and 51 are connected to the positive side of a source of electricity 52, while the contacts 27^a of said switches are connected to one terminal of one of the lamps 49 whose other terminal is connected with one of the terminals of the other lamp 49. The remaining terminal of said other lamp 49

is connected to the negative side of the source 52, and it will thus be seen that when a train approaches the crossing on either track, a switch 50 or 51 will be closed for lighting the lamps 49 and giving a visible warning that the train is approaching the crossing and that the gates are about to be closed.

The construction and operation will be readily apparent from the foregoing description, and minor changes may be made without departing from the spirit and scope of 10 the invention as claimed.

What I claim as new is:—

A pair of railroad crossing gates constructed and adapted to be automatically lowered below the surface of the roadway to open position and automatically raised above the roadway to closed position, and comprising each a pair of hollow pillars sunk below the 20 roadway and rising above the same, said pillars having slotted inner sides, a gate structure having a frame work with top and bottom rails projecting through the slots and vertically slideable therein, pulleys mounted 25 within and at the upper ends of said pillars, cables passing over said pulleys and attached to said gate, a horizontal shaft passing through said pillars below the roadway, winding drums mounted on said shaft and 30 having wound thereon said cables, and means connected with said shaft, and with train controlled devices, whereby said gate is raised and lowered by the passing of a train over 35 said devices and means including sprocket wheels and chains whereby operative movement is conveyed from the motor shaft of one gate to the other gate.

In testimony whereof I affix my signature.
VITO GALIZIA.
